UNITED STATES PATENT OFFICE

SIDNEY L. LONG, OF MINNEAPOLIS, MINNESOTA

TOY

Application filed July 29, 1929. Serial No. 381,832.

My invention relates to toys, and an object is to provide a device of this character which is not only attractive and amusing but produces a variety of movements of movable parts which are puzzling and instructive. In carrying out my invention, I provide a standard upon which two riders are mounted, the device being so constructed and arranged that a wobbling movement is imparted to one of the riders and this wobbling movement imparting a movement to the other rider which is different in character from the movement of the first rider. The riders may be of different shapes such as disks, plates and bars and they are designed to carry various representations such as representations of living objects. Any suitable means such as spacer means may be employed between the two riders whereby the movement of the first rider imparts a different movement to the second rider.

The full objects and advantages of my invention will appear in connection with the detailed description thereof, and the novel features of my inventive idea will be particularly pointed out in the claims.

In the accompanying drawings which illustrate my invention embodied in practical form,—Fig. 1 is an elevational view of the device with a small portion shown in section. Fig. 2 is a fragmentary sectional view showing spacer means arranged differently from Fig. 1. Fig. 3 is a plan view of the primary rider. Fig. 4 is an enlarged sectional view showing one position assumed by two rider members and interposed spacer means. Fig. 5 is a similar view showing said parts in another position. Fig. 6 is a diagrammatic view illustrating the manner in which the primary rider imparts movement to the secondary rider. Fig. 7 is an elevational view showing toy figures carried by the secondary rider. Fig. 8 is a view corresponding to Fig. 4. Fig. 9 is a view corresponding to Fig. 5. Fig. 10 is a view in section of the line 10—10 of Fig. 8.

Referring to the drawings, Figs. 1, 2, 4, and 5 show a standard 10 around which there is a helical rib or thread which may be produced in any suitable manner. As shown,

this thread is in the form of a coiled wire 12, the lower end of which is secured to a base member 14 by which the standard is supported. A ball 15 placed on the upper end of the standard engages the upper end of the coiled wire 12. A primary rider 16 and a secondary rider 18 are mounted on the standard 10. The rider 16 has a hole 20, the diameter of which is slightly less than that of the thread 12 but is slightly greater than that of the standard 10 whereby this rider moves freely with relation to the standard and may have a reciprocating movement but at the same time is restrained by the thread so as to be given thereby a movement of rotation as it moves downwardly by gravity. The rider 18 has a hole 22, the diameter of which is greater than that of the thread 12 so that the movement of this rider is not affected by the thread. In the embodiment shown, the riders are in the form of disks and are made of sheet material such as transparent celluloid. In Fig. 3, the primary rider 16 has representations of waves 24 painted or otherwise produced thereon. The secondary rider 18 is left entirely transparent so that it is easy to see therethrough. The primary rider 16 is thinner than the distance between adjacent convolutions of the thread 12. The result is that when this rider is placed at the upper end of the thread, it will work its way downwardly by gravity so that a wobbling movement is imparted thereto. This wobbling movement consists of two components, one of which is a reciprocating or up-and-down swinging movement occurring at diametrically opposite sides of the standard progressively and the other of which is a rotating movement around the axis of this rider. In the embodiment shown, there are about twelve reciprocations for each rotation of the primary rider. The relative number of reciprocations may be readily varied by varying the pitch of the thread. Both of the riders may be provided with representations which will add to the attractiveness of the device. As shown, the primary rider 16 carries representations of fish 26 which are headed in a counter-clockwise direction while the secondary rider 18 carries representations 136

of fish 28 which are headed in a clockwise direction. Operating means are placed between the two riders whereby the movement of the primary rider imparts a movement of a different character to the secondary rider.

5 In the embodiment shown, such means consists of two spacer elements 30 and 32. The element 30 is in the form of a ring which as shown in Figs. 1, 4, and 5 is located on top 10 of the rider 16, with the standard and thread passing through the hole 34 of the ring. The hole 34 is of such size that the ring 30 will be given the wabbling movement of the rider 16 without interference from the thread 12. The spacer element 32 is in the form of 15 an elongated bead and is located between the ring 30 and the rider 18 with this rider resting directly upon or if desired secured to the element 32. The hole in the bead 32 is of 20 such size that the bead will slide freely on the thread but is not of sufficient size to pick up the wabbling movement of the primary rider 16. With the parts arranged as shown in Figs. 1, 4, and 5, the operation of the device will be understood by referring to the 25 diagram shown in Fig. 6. Since the thread 12 is a right hand thread, the rider 16 will rotate in counter-clockwise direction as it moves by gravity down the standard. The 30 rider 16 will at the same time acquire a reciprocating or swinging movement which in combination with the rotative movement produces the wabbling movement previously referred to. This swinging movement as 35 viewed from any fixed position will be between the limits shown in Figs. 4, 5, and 6. By referring to Fig. 6, it will be understood how the swinging movement and the rotative movement of the rider 16 constitute components which combine to give the rider the 40 wabbling movement. It is apparent that as the rider 16 reciprocates or swings, its axis moves through the angle A which is equal to the angle B representing the extent of swinging movement of the rider. The shifting of 45 the axis of the rider 16 combined with the rotative movement of the latter causes all points in the upper edge of the ring 30 to move around in a small circle, the direction of movement in the circles being counter-clockwise as the device is viewed in the drawings. The result is that as this rider rotates forwardly the upper edge of the ring 30 imparts a succession of back thrusts to the lower 50 edge of the bead 32 so that this bead and the rider 18 carried thereby are caused to rotate in the opposite direction from that in which the rider 16 is rotating. There are a plurality of these backward thrusts for each rotation of the disk or rider 16 and therefore the rider 18 is caused to rotate faster than the rider 16. By referring to Figs. 4 and 5, it will be understood that the rotation of the bead 32 in reverse direction is assisted on account of a slight tilting thereof produced by

the wabbling movement of the ring 30. This tilting follows the wabbling movement of the ring 30 around the standard and causes the edge of the bore of the bead to impinge progressively on the thread 12 in such manner that there is a tendency to screw the bead backwardly on the thread. When the rider 16 has reached the lower end of its travel, it comes to rest upon a bead 36 which at this time is resting upon the base member 14. By grasping the bead 36, the riders may be quickly slid to the upper end of the standard, it being understood that when sufficient force is applied, the rider 16 will slide over the thread 12. If a spacer element which cannot wabble with the rider 16 is placed thereon, then the secondary rider 18 instead of rotating in the reverse direction will rotate in the same direction as the primary rider 16. This result may be accomplished by placing the bead 32 on top of the rider 16, the ring 30 being placed on top of the bead 32 as shown in Fig. 2 in order to give the necessary clearance for the objects 26 carried by the rider 16. Either or both of the riders may be provided with objects such as representations of living objects which will add to the attractiveness of the toy. When such representations are in the form of fish as shown, and with waves depicted on the lower rider, the fish carried by this rider will appear to be swimming around in the opposite direction when the device is set up in the manner first described. If the arrangement shown in Fig. 2 is employed, however, then the fish carried by the upper rider will appear to be swimming backwardly.

Figs. 7 to 10 show how the primary and secondary riders may be employed to impart individual motion to toy figures carried by the secondary rider. In this embodiment of the invention, the spacer element 30' is in the form of a ring having the inner surface of its upper edge rounded out so that the lower end of the bead 32' may extend down somewhat into the ring. The bead 32' is shorter than the bead 32 previously referred to and instead of directly engaging the lower surface of the rider 18, engages the lower end of a tubular member 36 which extends down from the material of the rider 18 surrounding the hole 22 therein. The ring 30', the bead 32', and the tube 36 constitute spacer elements by means of which the oscillating and rotating motion of the rider 16 causes a rotary motion to be imparted to the rider 18. Unless the rotating movement of the rider 18 is restrained, it will be in the opposite direction from the rotating movement of the rider 16 for the reasons previously set forth in detail. However, the rider 18 is shown provided with openings 38 which receive toy figures or dolls 40 preferably made of hollow celluloid. The dolls are supported by pushing their lower portions through the holes 38 so that the dolls are sus-

pended by their arms 42 resting upon the rider 18. The holes 38 are of such size that the dolls may be pushed into place accompanied by a slight collapsing of the abdomens thereof. This feature prevents the dolls from becoming detached unless force for this purpose is exerted but at the same time they are sufficiently free to have an individual movement of their own. The dolls are of such length that their feet 44 stop short of the primary rider 16 when the latter is in horizontal position as shown in Fig. 7. However, when the wabbling or combined oscillating and rotating movement of the rider 16 starts, the feet of the dolls will drag on this latter rider when it assumes the tilted position shown in Figs. 8 and 9. The frictional engagement of the feet with the rider 16 prevents the rider 18 from rotating in the opposite direction from the rider 16 and causes it to rotate in the same direction as the rider 16 but at a slower rate of speed. As will be seen further from Figs. 8 and 9, the tilting of the rider 16 exerts an upward thrust upon the dolls, thereby lifting them as shown at the left in Fig. 8 and at the right in Fig. 9. This lifting movement especially in connection with the dragging of the feet upon the rider 16 causes the dolls to have a dancing movement.

I claim:

1. In a device of the class described, the combination of a standard, a primary rider mounted on said standard, means associated with said standard for causing a wabbling movement of said primary rider, a secondary rider mounted on said standard, and means between said riders for causing said wabbling movement to impart a movement to said secondary rider which is different in character from the movement of said primary rider.

2. In a device of the class described, the combination of a standard, a primary rider mounted on said standard, means associated with said standard for causing a wabbling movement of said primary rider, a secondary rider mounted on said standard, and means between said riders for causing said wabbling movement to impart a movement of rotation to said secondary rider.

3. In a device of the class described, the combination of a standard, a primary rider mounted on said standard, means associated with said standard for causing a wabbling movement of said primary rider, a secondary rider mounted on said standard, and means between said riders for causing said wabbling movement to impart a movement of rotation to said secondary rider in a direction opposite to that in which said primary rider is rotating.

4. In a device of the class described, the combination of a standard, a primary rider mounted on said standard, means associated with said standard for causing a wabbling movement of said primary rider, a second-

ary rider mounted on said standard, and spacer means between said riders upon which said secondary rider rests and by which a movement of rotation is imparted to the latter rider by said wabbling movement.

5. In a device of the class described, the combination of a standard carrying a helical thread, a primary rider having a hole through which said thread passes, the diameter of said hole being slightly less than that of said thread whereby a wabbling movement is imparted to said primary rider as it descends by gravity, a secondary rider having a hole through which said thread passes, the diameter of said latter hole being greater than that of said thread, and spacer means between said riders upon which said secondary rider rests and by which a movement of rotation is imparted to the latter rider by said wabbling movement.

6. In a device of the class described, the combination of a standard carrying a helical thread, a primary rider having a hole through which said thread passes, the diameter of said hole being slightly less than that of said thread whereby a wabbling movement is imparted to said primary rider as it descends by gravity, a secondary rider having a hole through which said thread passes, the diameter of said latter hole being greater than that of said thread, a spacer member having a hole whose diameter is greater than that of said thread and resting upon said primary rider, and a spacer member having a hole whose diameter is substantially the same as that of said thread interposed between said first spacer member and said secondary rider and upon which the latter rests directly.

7. In a device of the class described, the combination of a standard, a primary rider mounted on said standard, means associated with said standard for causing a wabbling movement of said primary rider, a secondary rider mounted on said standard, means between said riders for causing said wabbling movement to impart a movement to said secondary rider which is different in character from the movement of said primary rider, and representations of living objects carried by at least one of said riders.

8. In a device of the class described, the combination of a standard, a primary rider mounted on said standard, means associated with said standard for causing a wabbling movement of said primary rider, a secondary rider mounted on said standard, means between said riders for causing said wabbling movement to impart a movement of rotation to said secondary rider, and representations of living objects carried by at least one of said riders.

9. In a device of the class described, the combination of a standard, a primary rider mounted on said standard, means associated with said standard for causing a wabbling

movement of said primary rider, a secondary rider mounted on said standard, spacer means between said riders upon which said secondary rider rests and by which a movement of rotation is imparted to the latter rider by said wobbling movement, and representations of living objects carried by at least one of said riders.

10. In a device of the class described, the combination of a standard, a primary rider mounted on said standard, means associated with said standard for causing a wobbling movement of said primary rider, representations of waves carried by said primary rider, a secondary rider mounted on said standard, and means between said riders for causing said wobbling movement to impart a movement of rotation to said secondary rider, said secondary rider being transparent whereby said primary rider may be viewed therethrough.

11. In a device of the class described, the combination of a standard, a primary rider mounted on said standard, means associated with said standard for causing a wobbling movement of said primary rider, representations of waves carried by said primary rider, a secondary rider mounted on said standard, means between said riders for causing said wobbling movement to impart a movement of rotation to said secondary rider, said secondary rider being transparent whereby said primary rider may be viewed therethrough, and representations of living objects carried by at least one of said riders.

12. A toy comprising a standard surrounded by a helix, a disk slidable on said helix and adapted to gravitate from top to bottom thereof with an oscillating and rotating motion, a second disk on said standard, and means between said disks actuated by the oscillation and rotation of the first disk for causing the second disk to rotate.

13. A toy comprising a standard surrounded by a helix, a disk slidable on said helix and adapted to gravitate from top to bottom thereof with an oscillating and rotating motion, a second disk on said standard, and spacer means between said disks actuated by the oscillation and rotation of the first disk for causing the second disk to rotate in reverse direction.

14. A toy comprising a standard surrounded by a helix, a disk slidable on said helix and adapted to gravitate from top to bottom thereof with an oscillating and rotating motion, a second disk on said standard spaced above the first disk, and toy figures carried by the second disk which are disposed in such manner as to be given an individual movement by the oscillation and rotation of the first disk.

15. A toy comprising a standard surrounded by a helix, a disk slidable on said helix and adapted to gravitate from top to bottom

thereof with an oscillating and rotating motion, a second disk on said standard, spacer means between said disks actuated by the oscillation and rotation of the first disk adapted to cause the second disk to rotate, and toy figures carried by the second disk which are disposed in such manner as to be given an individual movement by the oscillation and rotation of the first disk.

16. A toy comprising a standard surrounded by a helix, a disk slidable on said helix and adapted to gravitate from top to bottom thereof with an oscillating and rotating motion, a second disk on said standard spaced above the first disk, said second disk containing openings, and toy figures movably supported in said openings in such manner that they receive an upward thrust from the oscillation of the first disk whereby a dancing movement is imparted to said figures.

17. A toy comprising a standard surrounded by a helix, a disk slidable on said helix and adapted to gravitate from top to bottom thereof with an oscillating and rotating motion, a second disk on said standard, spacer means between said disks actuated by the oscillation and rotation of the first disk adapted to cause the second disk to rotate, said second disk containing openings, and toy figures movably supported in said openings in such manner that they receive an upward thrust from the oscillation of the first disk whereby a dancing movement is imparted to said figures.

18. A toy comprising a standard provided with a helical rib, a pair of spaced elements mounted on said standard and adapted to gravitate down the same along said rib, one of said elements coacting with the rib and caused thereby to rotate and oscillate, and means actuated by movement of the last-named element to rotate the other element in the opposite direction.

In testimony whereof I hereunto affix my signature.
